CENTRIFUGAL VIBRATOR

Jes Asmussen, Milwaukee, Wis., assignor to A. O.
Smith Corporation, Milwaukee, Wis., a corpora-
tion of New York

Application February 9, 1938, Serial No. 189,563

4 Claims. (Cl. 233—5)

This invention relates to an improved apparatus for classifying ores in which centrifugal force is applied to concentrate particles having a high specific gravity such as gold and precious metals.

5 In this machine the ore containing pulp is forced into riffle grooves, the contour of which is changed at periodic intervals to vibrate the concentrates and re-classify the particles deposited.

It is an object of the present invention to provide 10 an improved machine for concentrating ore particles.

A further object is to provide a concentrator with riffles for collecting ore particles, the contour of which may be changed by the application 15 of hydraulic pressure to agitate the concentrates.

Still another object is to provide a fluid container defining a riffle surface on one side thereof, which may be displaced by variations in the fluid pressure to either widen and narrow the grooves 20 between riffles or to lessen the depth of the riffle grooves.

It is also the object of this invention to provide a centrifugal concentrator with horizontal riffles arranged on the inside of the bowl which may be 25 periodically vibrated at intervals independent of the speed of rotation of the bowl.

One embodiment of the invention is illustrated in the accompanying drawing which is a vertical cross sectional view of a rotary bowl, the section 30 being taken along the axis of the bowl.

Referring to the drawing the bowl 1 is mounted on a vertical shaft 2 journalled in any suitable bearing 3. The method of mounting and rotating the bowl forms no part of this invention and 35 the apparatus illustrated is intended to be more or less diagrammatic. Rotation of the bowl may be effected by a pulley 4 mounted on the shaft 2, driven by a belt 5 connected to any suitable power means.

40 Disposed around the inside of the bowl and suspended from the top where it is clamped between the flanged rim 6 of the bowl and a ring 7 by means of a number of bolts 8 is a bellows 9 of rubber or similar material. The outer wall of the bellows lies flush against the inner wall of the bowl, while the inner wall of the bellows is formed 45 to provide a series of riffles extending around the bowl transverse to the bowl axis. The riffle sleeve formed by the inside of the bellows must be flexible and for this purpose rubber is well adapted, although any material possessing similar characteristics may be employed.

45 The riffles are reenforced by a series of annular members 10, horizontally disposed, preferably having their inner faces attached to the most ex-

tended portions of the riffles. The members 10 are more rigid than those sections of the riffles which lie between the supported portions and form the base of the riffle grooves. Accordingly these members, when made of the same material 5 as the riffles, are thicker in cross section than the base of the grooves, but it is contemplated that they may be the same thickness when made of harder material.

The outer ends of the annular members 10 are 10 spaced a slight distance from the outer walls of the bellows to permit communication between the chambers created by such members. Notches 15 may be provided in the outer periphery of the members 10 at various intervals to facilitate this communication.

The lowest riffle is spaced some distance above the bottom of the bellows with the result that there is a fairly large sized chamber 11 below 20 the first riffle-supporting annular member. The volume of fluid contained in this chamber must be maintained substantially constant and consequently the walls are preferably made of fabric which will resist expansion upon the application of internal pressure.

25 Stretched across the bottom of the bowl and connecting the inner sides of the bellows at a point a short distance below the first riffle is a sheet 12, likewise of rubber or similar material. This sheet may be formed as a continuation of the inner 30 wall of the bellows as illustrated in the drawing. Chamber 11 is constructed below the riffles and the sheet 12 in order that the pulp thrown out in the bowl will not impinge against the walls of the chamber to distort its contour or affect 35 the pressure within the bellows. Consequently the external pressure on the chamber 11 will be maintained at substantially uniform atmospheric pressure, and the variations in internal pressure may be accurately controlled.

40 For varying the pressure within the bellows, the chamber 11 communicates by means of tube 13 with a diaphragm pump 14 actuated by suitable power means not shown. To provide a rotatable connection in the conduit, tube 13 communicates with a port through the center of the bowl shaft 2 and connection is made with the conduit 15 leading to the pump 14 by means of a suitable fitting 16 provided with customary packing to prevent leakage.

45 The pressure system just described may be economically operated with water as the fluid medium. With a bowl adapted to be operated in the neighborhood of 1000 revolutions per minute, variations in fluid pressure are caused to 50

55

occur at a rate of around 100 to 120 per minute.

Pulp is fed to the bowl by means of the centrally disposed feed pipe 17 which discharges a slight distance from the bottom of the bowl. As the bowl is rotated the pulp is forced outwardly and upwardly over the riffle surface surrounding the interior of the bowl and finally flows over the top. Any suitable basin may be provided for discharged pulp such as a trough surrounding the bowl. No such means are shown because they are conventional and well known by those familiar with this art.

Ordinarily if the riffle contour remained unchanged during the concentration of the ore, particles of heavier specific gravity would be thrown into the grooves between riffles together with sand and other lighter undesirable particles. This mass of particles soon becomes solidly packed in the grooves and further classification becomes impossible.

By varying the pressure in the bellows, the contour of the riffles may be changed a number of times during the process to loosen up the particles deposited in the grooves and eventually 25 to work the lighter particles out of the bowl, with the result that better classification of heavier, desirable particles can be obtained. Increasing the pressure lengthens the bellows spreading the riffles apart and creating a 30 shallower, broader groove, which permits the pulp stream to sweep out lighter particles. At the same time a broader surface is provided for the deposition of additional heavier particles from the pulp stream.

35 When the pressure is decreased, the riffles resume their original position and the grooves are deep and narrow, retaining heavier particles and expelling lighter particles. Pressure impulses are controlled by the diaphragm pump entirely 40 independent of the speed of rotation of the bowl and may be varied for different ores and under different working conditions.

The invention having been described what I claim and desire to secure by Letters Patent of 45 the United States, is:

1. In a rotary bowl for classifying materials of different specific gravities, a flexible sleeve defining a series of riffles arranged transversely to the bowl axis, said sleeve being disposed inside said bowl and spaced therefrom, a fluid chamber between said riffles and the sides of the bowl, and means for changing the contour and width of the riffles by varying the fluid pressure in said chamber.

2. In a rotary bowl for classifying materials of different specific gravities, a bellows of flexible material disposed around the inside of the bowl and adjacent the walls thereof, said bellows having a series of riffles arranged on the inner side thereof, fluid medium maintained within 15 said bellows, and means for varying the pressure of said fluid medium to vary the contour and width of the riffles.

3. A centrifugal concentrator which comprises a bowl, a flexible riffle sleeve disposed around the inside of the bowl and radially spaced therefrom, a fluid chamber between said riffle sleeve and said bowl, spaced annular members reinforcing said riffle sleeve and forming a number of compartments in said fluid chamber, the reinforcing 20 members carried by said flexible riffle sleeve being free to move axially upon the lengthening or shortening of the sleeve, means for fluid communication between said compartments, and means for varying the fluid pressure within said 25 chamber to flex the riffles and agitate the ore particles deposited in the riffles by varying the length of the sleeve and correspondingly varying the width of the riffles.

4. A centrifugal concentrator of the rotary 35 bowl type which comprises a bowl, a bellows suspended inside said bowl, the inner surface of which has a series of riffles arranged transversely to the direction of flow of ore pulp in the bowl, fluid medium maintained within said bellows, a 40 pump, and means for transmitting pressure impulses from said pump to said bellows to open and close the grooves between said riffles.

JES ASMUSSEN.
